UNITED STATES PATENT OFFICE

172,101

TELEVISION CART

Kenneth V. Long, Colorado Springs, Colo.

Application April 27, 1953, Serial No. 24,695

Term of patent 7 years

(Cl. D14—3)

To all whom it may concern:

Be it known that I, Kenneth V. Long, a citizen of the United States, residing at 1311 So. Nevada Ave., Colorado Springs, State of Colorado, have invented a new, original, and ornamental Design for a Television Cart, of which the following is a specification, reference being had to the accompanying drawing, forming a part hereof.

Figure 1 is a front perspective view of a television cart showing my new design; and

Figure 2 is a rear perspective view thereof.

I claim:

The ornamental design for a television cart, as shown.
